UNITED STATES PATENT OFFICE.

MORIS MOOSE, OF CHICAGO, ILLINOIS.

BUTTON AND ORNAMENT PASTER.

SPECIFICATION forming part of Letters Patent No. 400,353, dated March 26, 1889.

Application filed April 21, 1888. Serial No. 271,410. (No model.)

To all whom it may concern:

Be it known that I, MORIS MOOSE, a citizen of the United States, residing at Chicago, in the county of Cook and State of Illinois, have 5 invented a new and useful Improvement in Button and Ornament Pasters, of which the following is a specification.

It is the custom of manufacturers of buttons, dress ornaments, and the like small articles, to fasten their wares, for convenience in shipping and handling, upon sheets of card-board. Usually, and more especially in the case of the smaller buttons and ornaments, the cards hold numbers of dozens of 15 the article, which are arranged in rows, and by a system of fastening commonly practiced a continuous thread serves to retain all or a number of the articles upon the card. It is customary for retailers of the buttons and 20 ornaments thus secured, when fewer of the articles than a card contains are desired by a purchaser, to cut from the card a section carrying the desired number. This naturally severs and loosens the thread which serves 25 to retain the remainder of the article left upon the card, which latter is therefore liable, with handling, to separate from the retaining medium.

My object is to provide means for overcoming this difficulty.

To this end my invention consists in a button and ornament paster comprising a block composed of paper sheets gummed on one side and fastened together toward two opposite edges.

In the drawings, Figure 1 is a perspective view of my improved paster, and Figs. 2 and 3 broken plan views of one end of the same, showing two ways of fastening the sheets together toward the edges.

A is the block, of which A' is the back, composed, preferably, of stiff pasteboard, and A² the cover, of like material.

B represents sheets of thin paper or an 45 equivalent material for my purpose, each gummed on the side toward the cover A², the sheets being fastened together and to the back

A', and, as to the upper edge, (where they may be perforated, as shown, to afford tearing-lines,) also to the cover, by means of staples s. The fastening of the sheets, as described, holds them flat and prevents their tendency to curl.

C is a strip of thin sheet metal, preferably of the shape shown, and D a sponge, both of which serve as adjuncts for purposes herein-after described.

The gummed sheets of paper are designed more especially for the convenience of retailers of buttons and ornaments, to enable them readily to secure the buttons or ornaments upon the cards which contain them in a manner to prevent their becoming loosened with the severance of the thread, where a section of the card is cut off, the fastening effect being produced by a sheet of the gummed paper applied upon the connecting-thread to the back of the card. The block A affords a convenient means for keeping a supply of gummed sheets close at hand and ready for use when required. It is used as follows: The cover A² being first thrown back, the plate C is inserted under the top gummed sheet, B, as shown, and the gummed surface of the latter dampened by means of the sponge D, previously moistened for the purpose. The plate C is then tilted upward, causing it to tear the dampened sheet from the fastenings s, and the sheet is then applied to the back of the card. The plate C, in addition to affording convenient means for tearing off the dampened sheet, prevents the moisture from penetrating to the gummed sheets underneath.

What I claim as new, and desire to secure by Letters Patent, is—

As a new article of manufacture, a button and ornament paster comprising sheets of paper gummed on one side and fastened together into blocks toward two opposite edges, substantially as described.

MORIS MOOSE.

In presence of—

J. W. DYRENFORTH,

M. J. BOWERS.
